UNITED STATES PATENT OFFICE.

JOSEPH B. CLAY, OF CEDAR FALLS, IOWA.

GATE-LATCH OR THE LIKE.

1,347,991.

Specification of Letters Patent. Patented July 27, 1920.

Application filed April 1, 1916. Serial No. 88 220.

To all whom it may concern:

Be it known that I, JOSEPH B. CLAY, a citizen of the United States, residing at Cedar Falls, in the county of Blackhawk and State of Iowa, have invented certain new and useful Improvements in Gate-Latches or the like, of which the following is a description.

My invention belongs to that general class 10 of devices known as gate latches, and relates particularly to a device adapted for locking a swinging gate, and especially that type of gate that may be swung in either direction. The invention has among its objects the production of a device of the kind 15 described that is simple, convenient, durable, efficient and satisfactory, that may be used wherever found applicable. The invention particularly has among its objects the production of a device that will securely lock 20 the gate, whether the rigid or tilting type, whether tilted or not, at different points at the free or swinging end of the gate, but which device may be easily controlled to 25 release the gate. With the latch herein described stock will not be accidentally injured by the same. The latch mechanism is also protected from the weather in a simple and efficient manner. It also has 30 among its objects the production of a device, which, when the gate is pushed or thrown shut, will automatically lock the gate shut by the closing movement of the gate.

To this end my invention consists in the 35 novel construction, arrangement and combination of parts herein shown and described, and more particularly pointed out in the claims.

In the drawings, wherein like reference 40 characters indicate like or corresponding parts,

Figure 1 is a view in elevation of a gate having my latch applied thereto;

Fig. 2 is a front elevation and partial sectional view of a portion of the preferred 45 form of latch;

Fig. 3 is a side elevation and partial sectional view of a portion of the same;

Fig. 4 is a sectional view taken substantially on line 4, 4 of Fig. 6;

Fig. 5 is a front elevation showing the latch member thrown to one side, as indicated in the dotted lines in Fig. 4;

Fig. 6 is a sectional view taken substantially on line 6, 6 of Fig. 4, showing the 55 complete device, and

Fig. 7 is a sectional view taken substantially on line 7, 7 of Fig. 2.

Referring to the drawings, in which the preferred form of my device is shown, 1 and 2 represent any style of the fence or gate posts, between which is arranged the gate of any suitable type. The gate shown consists of the end bars 3 and 4, and connecting bars 5, 5, the same being pivotally connected together in the gate shown, at points 6, 6, etc. The gate may be covered with any suitable wire, wire netting, or fabric, this depending to a large extent upon the particular use to which the gate is to be put. In 70 the gate shown end bar 3 is pivotally secured to the post 1 by hinge members 7, 7, it being understood that the particular manner of hanging the gate forms no part of the present invention. It may also be mentioned 75 that the gate illustrated is of the tilting adjustable type, so that the free end of the gate may be raised or lowered, this being particularly mentioned because the latch or locking device herein described is applicable for 80 this type of adjustable gate, regardless of its adjustment.

The particular latch or locking device shown consists substantially of two or more latch or locking devices arranged to be actuated or controlled as one; either one, however, being adapted to be used alone should only one be desired. A description of one will suffice for both, as they are substantially identical. As shown, 8 is a base plate arranged to be secured to the fence post 2 by bolts or screws 9, the particular design or shape of the same and method of fastening the plate 8 to the post depending upon the style of post to which it is to be attached. 90 Plate 8 is provided with a pair of spaced horizontally extending flanges 10 and 11, and is preferably cut away or recessed as at 13 between the flanges on each side thereof (see Figs. 6 and 7). The same is also formed with extending lugs 12, the purpose of the same being more fully explained hereafter. Arranged between the spaced flanges 10 and 11 is a latch member 14, formed with extending or forked arms 15, 15, the latch member being substantially U-shaped in the preferred construction. The latch member is preferably enlarged at the ends of the forked arms, as shown, so that the stock will not be injured in case they should accidentally strike the latch member 105 110

in passing through the gateway. The latch member is pivotally secured in place by a pin or bolt 16 extending through the flanges and latch member, and is formed with shoulders 17, 17 at each side, as most clearly shown in Fig. 7. In the preferred construction I provide suitable means for yieldingly opposing the movement of the latch members. In the construction shown I employ 10 spring washers 25, which are substantially brakes, and prevent the latch members from turning too far or rebounding when thrown to the open position.

The upper flange 10 is formed with openings 10' therethrough at each side, through which project the stops or pins 18. The pins shown are formed with heads 19 elongated, which prevent their dropping through the openings through the flange, and the 20 same may be offset or formed with lips at the lower ends, as indicated at 20 (see Figs. 5 and 7) or in an equivalent manner, to prevent their being raised and withdrawn entirely from the flange. This is most clearly 25 shown in Figs. 3, 5 and 7. The openings in the pins are preferably elongated, the purpose of this being more fully explained hereafter. I have shown the flange slightly countersunk on the lower side about the 30 openings, so that the pins may be raised or withdrawn to a point where they do not project below the flange. They are of a length to project into the path of the latch member 14, and when the same is in closed 35 position, the shoulders 17 of the latch abut against the pins, thereby preventing the pivotal movement of the latch member about the bolt 16. They are preferably of sufficient length to project below the latch member 40 and bear against the lugs 12 previously referred to. This affords a very rigid construction, as when the pins are dropped in stopping position, the pins have a bearing at each end, between which they are engaged 45 by the latch member.

The two pins are connected preferably loosely by a link 21, which in the construction shown is formed with hooked ends arranged to extend through eyes 19, or elongated 50 openings in the pins. The preceding description covers both of the latch members, which, as shown in the drawings, are the same, as previously mentioned. The links 21 of each latch member are connected 55 by an actuating rod 23, projecting through the upper flanges, to the upper link 21. By making openings through the heads of the pins elongated, the link connecting the pins is prevented from tipping back on the rod, 60 this applying particularly to the upper link, which might lock the parts about the link tipped back. Movement of the rod upward releases the latches, or that is, raises the pins, so that the latch members and gate 65 may be swung in either direction. Assum-

ing that the rod 23 is raised and the gate swung as indicated in Fig. 4, by the dotted lines, the pins being raised the latch members are free to swing with the gate, and permit the same to be opened. Owing to 70 the brakes, however, that is the spring washers 25, or their equivalents, the latches will not rebound, so that they could not be engaged by the gate upon its return movement. The rod may then be released, and 75 while the pins toward which the latch members and gate are thrown will rest upon and are supported by the latch members, owing to the flexibility or loose connection between the pins, the other pins will drop, as indicated in Fig. 5, so that they are in engaging position. When the gate is swung back to closed position, the same enters between the forks 15, 15 and moves the same back to the position indicated in the full lines in Fig. 4, 80 or Fig. 7, the pins in engaging positions stopping the gate and latches, and the pins that were supported by the latch members then drop into engaging positions, locking the gate shut.

I have shown the two latches described protected by a housing 26. The housing shown is formed with the ends 27 and with an extension 28, which is secured to the flange 10 by the bolt 16. Any equivalent 95 housing may, of course, be employed, or the manner of securing the housing shown in place may be modified. The housing prevents snow or rain settling on the links and pins and other parts of the latch covered thereby, and freezing, and possibly impairing the efficiency of the device.

It will be obvious that with this construction the gate is securely engaged or locked shut at more than one point, so that 105 stock bearing against it at the top or bottom cannot spring the same. One of the important advantages of the construction herein shown and described is that if the gate engages only one latch where two are 110 employed, owing to the tilting of the gate or sagging of the gate post, the device is entirely operative, the same as if both latches were engaged. The construction also permits the gate to be swung in either direction 115 and automatically locks it when turned to closed position. The latches are conveniently controlled in one operation by means of the rod 23, and it may be noted that while only two latch devices are shown connected by the rod, any number may be employed by arranging them intermediate the two devices shown, or at either side, and extending the rod so as to engage the additional link. If desired any suitable means 120 may be employed for drawing the rod down.

While two devices are shown as the preferred construction, it is, of course, obvious that one will work equally as well, and in the same manner, when only one device is de- 130

sired, the advantage of the two being merely locking of the gate near the top and bottom for the purposes set forth. Where only one of the devices is employed instead of 5 the plurality shown, the connecting link 21 might be omitted, although the construction would not be as convenient. Owing to the elongated openings through the heads of the pins 19, some play is permitted, so that the 10 latches are independently operable. In other words, when either the top or bottom latch member is closed, the pin for locking the same may engage the closed latch member, although the other latch member may 15 still remain open, and its corresponding locking pin shown remains raised. It is also obvious that the results and operation would be the same if the latches were mounted on the gate post 4 instead of on 20 the fence post 2 at the gate opening, or if a wooden gate was employed in place of the steel gate shown.

Having thus described my invention, it is obvious that various immaterial modifications may be made in the same within the 25 scope of the appended claims without departing from the spirit of my invention; hence I do not wish to be understood as limiting myself to the exact form, construction, arrangement and combination of parts 30 herein shown and described or uses mentioned.

What I claim as new and desire to secure by Letters Patent is:—

35 1. A gate latch of the kind described comprising a base plate provided with a projecting horizontal flange, a substantially U-shaped latch member arranged below and pivotally carried by said flange, a pair of 40 pins arranged at each side of said flange and movable downwardly therethrough in the path of said latch member, means on said pins for limiting the upward movement thereof, said U-shaped member having 45 shoulders arranged to normally abut against the projecting ends of said pins below the base plate flange.

2. A gate latch of the kind described, 50 comprising a base plate provided with a projecting horizontal flange, a substantially U-shaped latch member pivotally carried by said flange, a pair of pins arranged one at each side of said flange and movable therethrough, said pins offset at their lower 55 ends arranged to limit upward movement thereof, said U-shaped member having shoulders arranged to normally abut against said pins, and a link loosely connecting said pins, and means for raising said link.

60 3. In a device of the kind described and in combination, a plate provided with a pair of projecting horizontal flanges, a U-shaped member positioned between said flanges, and pivotally secured therebetween 65 on a vertical axis, a pair of pins arranged

to project through the upper flange, and movable into the path of said U-shaped member, said U-shaped member provided with shoulders arranged to abut against said pins, a link connecting said pins, and 70 means for controlling said link.

4. In a gate latch of the kind described, the combination of a pair of plates, each plate provided with a pair of spaced horizontal flanges, a U-shaped latch member for 75 each plate arranged between said flanges, means for pivotally securing said latch members in position, a pair of pins for each plate, said pins vertically adjustable and of a length to extend below the upper flange 80 in the path of said latch members, a link for and connecting each pair of pins, and a rod connecting said links.

5. In a gate latch of the kind described, the combination of a pair of plates, each 85 plate provided with a pair of spaced horizontal flanges, a U-shaped latch member for each plate arranged between said flanges, means for pivotally securing said latch members in position, a pair of pins for each 90 plate, said pins vertically adjustable and of a length to extend below the upper flange in the path of said latch members, abutments for the lower ends of said pins, said abutments integrally formed with said plates 95 and disposed below said latch member, a link for and connecting each pair of pins, and a rod pivotally connecting said links.

6. In a gate latch of the kind described and in combination, a base having a pair of 100 projecting horizontal flanges spaced from each other, a U-shaped latch member pivoted on a vertical axis between said flanges, said plate recessed below the upper flange on each side, said recesses of a size to receive 105 the edge of said latch member when moved to either of its extreme positions, said upper flange provided with an opening therethrough at each side adjacent the rear end of said latch member, a vertically movable stop projecting through each opening, said stops provided with heads for limiting the 110 downward movement of the same through said openings, and arranged at the lower ends with means for preventing the upward withdrawal of the same through said openings, and a link connecting said stops.

7. In a locking device of the kind described and in combination, a plurality of latches, each comprising a base having a 115 pair of projecting horizontal flanges spaced from each other, a U-shaped latch member pivoted on a vertical axis between said flanges, said upper flange provided with an opening therethrough, at each side adjacent 120 the rear end of said latch member, a vertically movable stop projecting through each opening, said stops provided with means for limiting the vertical movement thereof through said openings, and of a length to 125 130

engage said latch member, a link adjustably connecting each pair of stops, and a rod for actuating said links.

8. In a gate locking device of the kind described and in combination, a plurality of locking devices, each comprising a base plate arranged for adjustment to a fence post, and having spaced projecting flanges, a forked latch member pivoted on a vertical axis between said flanges, said base plate cut away between said flanges on each side thereof, vertically movable pins extending through the upper flange in the path of said latch member and arranged to engage the same when in central position, means for limiting the vertical movement of said pins, said plate provided with an abutment formed integral therewith in the plane of the lower flange, and of a length to engage the lower ends of said pins when dropped to operative engaging positions, a link loosely connecting said pins, and a rod pivotally connected to the lower link, and projecting through the flanges of the upper base plate and pivotally connected to the upper link, whereby the movement of said rod will control all of said pins.

9. In a gate latch of the kind described and in combination, a base plate provided with a pair of spaced horizontally extending flanges, a suitably shaped latch member pivotally supported between said flanges, resilient means for yieldingly opposing any movement of the latch member within its limit of travel, and means carried by one of said flanges and movable into the path of said latch member for normally engaging the latch member and preventing pivotal movement thereof.

40 10. In a gate latch of the kind described and in combination, a base plate provided with a pair of spaced horizontally extend-

ing flanges, a suitably shaped latch member pivotally supported between said flanges, resilient means arranged between one flange 45 and the latch member for yieldingly opposing any movement of the latch member within its limit of travel, and means carried by one of said flanges and movable into the path of said latch member for normally engaging the latch member and preventing pivotal movement thereof. 50

11. In a gate latch of the kind described and in combination, a base plate provided with a pair of spaced horizontally extending flanges, a suitably shaped latch member pivotally supported between said flanges, resilient means for yieldingly opposing any movement of the latch member within the limits of its travel, means carried by one 55 of said flanges and movable into the path of said latch member for normally engaging the latch member and preventing pivotal movement thereof, and a housing carried by the upper flange for substantially inclosing 60 said latch engaging means. 65

12. A gate latch of the kind described, comprising a base plate provided with a projecting flange, a substantially U-shaped latch member pivotally carried by said flanges, a pair of pins arranged at each side of said flange, and movable into the path of said U-shaped latch member, a link loosely connecting the said pins, and a vertically movable support for said link, said link 70 75 loosely carried by said support.

In testimony whereof, I have hereunto signed my name in the presence of two subscribing witnesses.

JOSEPH B. CLAY.
